UNITED STATES PATENT OFFICE.

GEORGE F. BALLAY, OF SAN JOSE, CALIFORNIA.

PUMP.

Application filed December 27, 1931. Serial No. 595,031.

To all whom it may concern:

Be it known that I, GEORGE F. BALLAY, a citizen of the United States, and resident of San Jose, in the county of Santa Clara and State of California, have invented a certain new and useful Improvement in Pumps, of which the following is a specification.

This invention relates to that class of machines operable as a pump when power is applied to operate the parts for the transportation of fluid.

The invention more especially relates to that type of machine known as rotary pumps, in which there is a casing or shell usually having a substantially cylindrical chamber in which there is operative a driving rotor carrying radial blades having a defined orbital movement with a resultant reciprocation of the blades or pistons in the guides or guide-forming portions provided on or formed in the rotor.

In the usual type of such rotary pump, one edge of the blades either has frictional contact on the inner cylindrical surface of the casing chamber, or the opposite edge travels in a track or follows along the surface of a cam, causing tremendous friction, producing rapid wear, taking excessive power, and ultimately resulting in the "freezing up" or stopping of the entire machine.

In that type of rotary pump, the blades project as they approach a given position materially beyond the periphery of the rotor, with the result that the resistance of the fluid on the exposed portions of the blades tends to rock and cant the blades and cause them to bind across the edges of their guide ways with undue friction.

It is one of the objects of the present invention to improve the construction of machines operative as a rotary pump, so that the mentioned friction with its resulting wear is practically eliminated.

In other words, it is an object of the invention to provide a simple, inexpensive, and practicable device attached to or formed on the rotor for carrying the blades as they pass the inner cylindrical surface of the casing chamber where the liquid

passes through the pump, improved means being provided for the effective bearing or supporting of the blades throughout their width dimension at any position of the blades; thus enabling them to run freely with respect to the rotor; also relieving them of all frictional contact against the peripheral surface of the casing chamber, and therefore, materially reducing the wear.

It is also an object of the invention to provide for connecting the pressure behind each end of the rotating side walls together and, therefore, equalizing all end thrusts against the rotor.

It is a further object of the invention to provide means for defining the orbital movement of the blades, allowing the blades to be radially disposed in the rotor, and carried by the rotor as they pass the inner cylindrical surface of the casing chamber between the suction and the discharge where the liquid travels through the pump.

The invention possesses other objects and features of advantage some of which, with the foregoing will be made manifest in the following description of the preferred form of the invention which is illustrated in the drawings accompanying and forming part of the specification.

It is to be understood that it is not intended to limit the invention to the embodiment shown by said drawings and descriptions, as variations may be adapted within the scope of the invention as set forth in the claims.

In the drawing,—

Figure 1 is a central, longitudinal sectional view of one type of pump involving the invention.

Figure 2 is a transverse section on line B—B of Figure 1, looking in direction of the arrows, the rotor being turned 30°, showing a chamber at its maximum capacity between the suction and the discharge.

Figure 3 is a central longitudinal sectional view of the rotor, showing the extended flanges or side walls.

Figure 4 is a side elevation of the flanged rotor, showing the series of improved guide-ways in the side walls.

Figure 5 is a central sectional view of one of the runner rings that provides for defining the orbital movement of the blades.

Figure 6 is a side elevation of one of the 5 runner rings.

Figure 7 is an end section of one of the piston blades.

Figure 8 is a central longitudinal sectional view of one of the piston blades.

10 Figure 9 is a side elevation of one of the piston blades.

The principal improvements consist, first, in providing a device for a rotor of a rotary pump with a series of improved effective extended bearings or guides onto which the blades run as they are projected beyond the body of the rotor in which they are telescopically operated, means being provided on the device to carry the blades from the 20 suction to the discharge and prevent them from having frictional contact on the peripheral surface of the casing chamber where the liquid travels through the pump; provision being made for equalizing the end 25 pressures against the rotor, and secondly a feature of the invention is the provision providing for the defining of the orbital movement of the blades.

30 The improvements may be embodied in any type of rotary pump in which there is a shell or casing 2, which obviously, may be built up in any suitable manner, the present illustration not being utilized as indicating the only form of casing in which the parts 35 may be mounted.

The shell preferably forms a substantial cylindrical chamber 3 of any diameter and through which there extends an eccentrically mounted driving shaft 4, on which is secured 40 what is commonly called the "rotor" 5, having a diameter considerably less than the diameter of the chamber 3 in which it operates and is eccentrically located with one side of the rotor running quite close to the 45 contiguous cylindrical inner wall of shell 2. In the present case the rotor approaches the top of the shell's inner surface, and therefore leaves a material space between the bottom of the rotor and the bottom inner surface of chamber 3. One side of the shell is provided with an inlet connection 6, and the opposite side is provided with an outlet connection 7; the inlet and outlet connections in this case extending laterally 50 from the peripheral walls of shell 2.

The rotor 5 is provided with a plurality of substantially radial guide-forming recesses or pockets 8 extending from end to end in the rotor and through the side walls

55 15. In each of the guideways 8 and 8^a respectively, there is slidably mounted a flat blade 9, hereinafter termed the "piston blade", and which when it is retracted, approaches the bottom of its respective guide 60 way 8 as shown in the upper part of the ro-

tor 5, Figure 2, and as the rotor rotates, the blades 9 relatively move outwardly to the maximum position shown by the lowermost piston blades 9 in Figure 2, and in which position, the blades are in their maximum driving position, forming a movable wall extending between the lower position of the rotor 5 and the opposite spaced bottom surface of the chamber 3.

As above stated, it is desirable to prevent the "piston blades" from having frictional contact on the inner cylindrical surface of chamber 3 and at the same time to prevent their binding on the transverse shoulders formed by the outer ends of the guide-ways 8 in the rotor 5, and this is readily accomplished by the provision of means effective to carry the blades as they pass the bottom inner cylindrical surface of chamber 3, and capable of guiding and supporting them at 85 all times to their outermost edges during the operation of the pump.

A preferred form of such means is here shown as comprising outwardly extending flanges or walls 15 provided on the rotor 5 and operative in recesses provided in the chamber end walls, the flanges extending preferably to and beyond the outermost position of the outer edges of the piston blades 9, and are slotted or provided with guides 95 coincident with the guide-ways 8 of the rotor as is shown by the extended guide-edges 8^a, Figure 3, and onto which edges the piston blades run in their outermost positions.

The guides are preferably cut through the 100 flanges to allow the piston blades to fit into a means beyond the ends of the flanges for controlling their orbital movement, and also to allow the pressure behind the ends of the flanges to travel through the rotor and become equalized.

The outermost edges of the slots 16 in the flanges 15 coincide with the bottom inner cylindrical surface of chamber 3, said bottom surface of the chamber being concentric 110 with the rotor 5, and as the rotor rotates, the piston blades 9 move outwardly until they reach the outer edges 16 of the slots 8^a in the flanges 15 and in which position they are held and carried on the flanges past the bottom inner cylindrical surface of the chamber 3, sufficient allowance being provided to prevent the blades from having frictional contact on said bottom surface of said chamber.

A very important feature of the invention is the construction of the parts so as to reduce as much "slippage" as possible, and also decrease "cavitation" in the pump. By the present construction, the suction side of the rotor is formed by one or rear face of each piston blade and by the contiguous faces ^a of the side-flanges of the rotor, and by the peripheral wall of the rotor. As the blades bear on the guides 8^a in the flanges, 130

and as the flanges rotate with the blades, there is no end clearance space as to the suction, and thus, a chamber is formed that rotates with the rotor.

5 It is the object to form the chambers so that one chamber or more is intaking and another or more discharging while a chamber is filled to its maximum capacity between the suction and the discharge, making 10 a series of continuous rotating chambers that relieves the pump of extreme cavitation when it pumps against high pressures, and as there is no end clearance space as to the suction chamber the slippage of fluid 15 through the pump is reduced.

Means are provided for determining the orbital movement and position of the several piston blades 9 and a preferred form of such means consists of a pair of runners in 20 the form of rings 10, of which there is one countersunk in each end cover 18 of shell 2, the rings being disposed eccentric with respect to the rotor sufficient to allow the blades to pass the top inner cylindrical 25 surface of the shell 2. Suitable connection is provided between the parallel rings 10-10 and the several piston blades 9, as shown in Figure 1, the ends of the piston blades extending through the flanges of the rotor and 30 enter into a given set of oblong holes 11 in rings 10-10.

The rings in this case are driven by the several piston blades 9, the holes being of a length sufficient to allow the blades to pass 35 the two centers. Sufficient allowance is also provided in the width of the holes 11 to permit the blades to be carried on the flanges of the rotor as they pass the lower inner cylindrical surface of chamber 3. After 40 the blades have passed the lower inner cylindrical surface of chamber 3, they are carried by the rings 10 past the top inner cylindrical surface of shell 2.

I claim:-

45 1. A machine operative as a pump, having a shell, an eccentric rotor therein, orbitally

controlled blades slidably mounted in the rotor, and means provided in the rotor to prevent the piston blades from having frictional contact on the inner cylindrical surface of the casing between the suction and discharge where the liquid travels through the pump. 50

2. A machine, operative as a pump, having a shell, an eccentric rotor therein, radial 55 piston blades mounted in the rotor, and means provided on the rotor to prevent the blades from having contact on the inner cylindrical surface of the casing during their movement by the rotor. 60

3. A machine, operative as a pump, having a casing, an eccentric flanged rotor therein, piston blades mounted in the rotor and means to prevent the blades from having frictional contact on the inner cylindrical 65 surface of the casing between the suction and the discharge where the liquid travels through the pump.

4. A machine, operative as a pump, having a casing, an eccentric rotor therein, orbitally 70 controlled blades slidably mounted in the rotor and means provided on the rotor to guide and support the orbitally controlled blades beyond the body of the rotor and carry the blades from the suction to the discharge. 75

5. A rotor for a rotary pump, having means on the rotor to prevent the blades from having frictional contact on the inner cylindrical wall of the casing where the liquid 80 passes through the pump.

6. A rotor for a rotary pump, having means beyond the body of the rotor for slidably supporting the blades, and carrying the blades from the suction to the discharge. 85

7. A flange for a rotor of a rotating pump, provided with means to prevent the blades from having frictional contact on the inner cylindrical surface of the casing where the liquid passes through the pump.

GEORGE F. BALLAY.
